UNITED STATES PATENT OFFICE

146,680

DESIGN FOR A TEXTILE FABRIC

Waldo Peirce, Pomona, N. Y.

Application January 18, 1947, Serial No. 136,243

Term of patent 3½ years

(Cl. D92—1)

To all whom it may concern:

Be it known that I, Waldo Peirce, a citizen of the United States of America, residing in Pomona, county of Rockland, and State of New York, have invented a new, original, and ornamental Design for a Textile Fabric, of which the following is a specification, reference being had to the accompanying drawing, forming part thereof, wherein,

The figure is a plan view of a textile fabric showing my new design. The dot and dash lines on the drawing outline a design unit, which unit is repeated in regular succession as indicated by the extensions beyond the unit boundaries.

I claim:

The ornamental design for a textile fabric, substantially as shown and described.

WALDO PEIRCE.
